UNITED STATES PATENT OFFICE.

WILLIAM H. R. TOYE, OF PHILADELPHIA, PENNSYLVANIA.

PERFECTING COLOR-PRINTING MACHINE.

SPECIFICATION forming part of Letters Patent No. 364,976, dated June 14, 1887.

Application filed July 17, 1886. Serial No. 208,325. (No model.)

To all whom it may concern:

Be it known that I, WILLIAM H. R. TOYE, a citizen of the United States, and a resident of Philadelphia, Pennsylvania, have invented 5 certain new and useful Improvements in Perfecting Color-Printing Machines, of which the following is a full, clear, and exact description, reference being had to the annexed drawings, making part hereof.

10 My invention has for its object the improvement of that class of color-printing presses which print in one or several colors upon one or both sides of a sheet of paper, cloth, or other material at one passage of the latter through the machine.

15 My machine may be used for either lithography, zincography, typography, or zylography. Where the printing is to be done in several colors, it is accomplished by subjecting the fabric to be printed upon to a series 20 of multiple impressions in its passage through the machine.

25 The nature of my improvements will fully appear from the following specification and claims.

30 In the drawings, Figure 1, Sheet 1, is an elevation of my machine. Fig. 2 is a detached broken cross-sectional view of the ink-roller rack attachment. Fig. 3, Sheet 2, is a front 35 elevation of the machine; Fig. 4, a contracted broken view of one end of a plate-cylinder, showing one of the endless bands passing over it.

35 In my drawings I have shown simply those parts which are necessary to display my improvements, omitting some parts which are old and well known to those skilled in the art.

40 A, Fig. 1, is the frame of the machine; B, the feed-board.

45 D and E are two large cog-wheels at the ends of two plate-cylinders, which latter print, say, the outside of the sheet. F G are similar cog-wheels at the ends of two plate-cylinders which print the inside of the sheet; H, a pulley driven by a belt, H', which drives the machine; I, a cog-wheel on the shaft of pulley H, which gears with large cog-wheels D and E, as shown, and drives them in the directions indicated by the arrows on these large cog-

50 wheels; J, a small cog-wheel possessing one-half the number of teeth of the wheel D, and

gearing with the latter. This small cog-wheel J drives a tympan or impressing cylinder to hold the fabric up against the plate-cylinder driven by cog-wheel D.

55 K is a small cog-wheel similar to wheel J, which drives an impressing-cylinder set to press against the plate-cylinder driven by cog-wheel E. Cog-wheel K engages with cog-wheel E.

60 Power is communicated from cog-wheel E, through cog-wheels L L' and connecting-rod L'', to cog-wheel M, which drives a tympan or impressing cylinder to hold the paper or other fabric against the plate cylinder driven by cog-wheel F.

65 N is a cog-wheel driving a tympan or impressing cylinder which holds the paper against the plate-cylinder driven by cog-wheel G. Wheel N is driven from cog-wheel M through the intermediate connecting gear-wheel, N'.

70 In Fig. 3, O is the tympan or impressing cylinder to plate-cylinder D', driven by the gear-wheel J. (See Fig. 1.) O' is a similar impressing-cylinder to hold the material being 75 printed against plate-cylinder F', and it is driven by gear-wheel M. The gear-wheel K, Fig. 1, drives a like impressing-cylinder to hold the material against plate-cylinder E', and gear-wheel N drives a similar impressing- 80 cylinder to hold the material against the plate-cylinder driven by cog-wheel G, said plate-cylinder being shown in broken view in Fig. 4, (marked G').

85 P P' are two flexible endless bands or belts for carrying the material being printed through the press. These bands are provided with holes P'', (see Figs. 3 and 4,) which engage with sprockets P''' on each end of cylinder G'. As this cylinder revolves, the bands are carried over the various cylinders and rollers around which they are passed.

90 Q Q' are idler carrying-rollers for bands P P'.

95 Q'' is a combined carrying and tension roller for these bands, and is provided at each end with a set-screw, Q''', which sets against the stationary frame, and when turned, by means well known in the art, sets the roller Q'' back from or nearer to the frame A, thus tightening or loosening the bands P P'. These bands 100 P P' are provided with grippers R R R, set upon cross-bars, which latter extend from

band to band transversely of the machine. (See Fig. 2.) These grippers seize the paper and press its edge upon the cross-bar R', with which latter each series of grippers is provided. The cross-bar R' and the bar upon which the grippers are mounted are attached to the two bands at their opposite ends, and serve to keep these bands apart and hold them in proper position in their traverse.

10 The grippers are the ordinary ones used in printing-presses to grip and hold the edge of the paper in its passage through the machine, and are operated in the way well known in the art. I will therefore give this mechanism no special description here. The endless bands P P' pass over and around the roller Q, between the impression-cylinder O and the plate-cylinder D', and between the impression-cylinder turned by the cog-wheel K and the 15 plate-cylinder E'. These two plate-cylinders are outside the bands, and the two impression-cylinders are on the inside thereof. Thence the bands pass over the carrying-roller Q', and between the impression-cylinder O' and the plate-cylinder F', thence between the impression-cylinder N and the plate-cylinder G'. The 20 two last named plate-cylinders are inside of the bands, and the two last-named impression-cylinders upon the outside thereof. Thus any 25 sheet carried by the bands P P' will be impressed upon one side by the plate-cylinders D' E' and upon the other by the plate-cylinders F' and G'. Thence the bands P P' pass over the tension-roller Q'' to the point of starting. The traverse of the endless bands is of course continuous while the machine is in operation.

30 S is the receiving board to catch the printed sheets as they fall from the grippers after they are printed.

T is an endless broad band or web of a width equal to the length of the impression-cylinders O' and that driven by cog-wheel N, which I will call N''. This web T passes over the cylinders O' N'' and downward around the roller T'. The latter is set in a long trough, T'', and is packed upon one side by the sponge T'''. Upon the other side of roller T' are scrapers T^{IV}, projecting from the inside of the trough and 45 adapted to impinge against the band or web T as it travels through the trough. This band T is moved by the revolution of the cylinders O' N'', and as it passes down its outer surface is cleansed by the sponge T''', and is scraped 50 in its upward movement by the scrapers T^{IV}. It will be seen that it must move with the same velocity as the bands P P', and consequently the same as that of the material being printed upon. Therefore, though it is pressed against 55 one surface of the latter by the impression-cylinders, it will move evenly with the same and receive any surplus color off the said surface and prevent the smearing of the impression-rolls, which it protects. It will then keep 60 on in its traverse and be cleansed and scraped in trough T'' and always present a clean surface to the material being treated. Very lit-

tle of the coloring-matter will come off the paper in any event, whereby the sponge will not often require renewal and the scrapers will not often have to be cleaned.

65 U U U U are inking-rollers to furnish ink or colors to the types, cuts, or curved plates upon the cylinders D', E', F', and G'. These rollers are made of the same materials as ordinary printers' ink-rollers, and are mounted between curved arms U', which are attached at one end to the standards U'', which latter are secured firmly upon the main frame. The arms U' are shown short; but in practice they 70 are about double the length shown, and may be made to carry any number of rollers.

V V V V are the adjustable bearings of the impression-cylinders, the adjustability being effected by the set-screws V' V'. These bearings are set in journal-boxes, (shown in dotted lines,) and are of the form common and well known in the arts. Their object is to set the impression-cylinders close to or farther away from the plate-cylinders. As I lay no claim to the 75 invention of these bearings, they will require no special description, as any skilled mechanic can construct them. V'' V'' (shown in dotted lines, Fig. 1) are cross-sectional representations of long grooves in the impression-cylinder O and that turned by cog-wheel K and plate-cylinders F' G', adapted and so located as to receive the gripping apparatus R R' as it reaches these cylinders in the traverse of the bands P P'.

80 W W are end views (partly in dotted lines) of two water-troughs, one under each of the plate-cylinders D' E'. These troughs are so close to the lower surfaces of these cylinders that when they are filled with moistened sponge the latter will come into contact with these surfaces and moisten the same when the machine is used for lithography or zincography, when such moistening is always necessary.

85 The band P, I make of strip steel, copper, brass, or other tenacious flexible material. Of course many equivalents of these materials will suggest themselves to the mind of a skilled mechanic—such as chain belting running on sprocket-wheels, wire cable, and linked plate belting, &c., one being used to each plate-cylinder. The ink is taken from the fountain by ordinary conveying-rolls, such as are well known to constructors of printing-presses. 90 This device being thus well known, I have not considered it necessary to show it in my drawings. When the ink is applied to the printing-rolls, it is evenly spread by the use of friction or cog-wheel gearing on the ends of 95 said rolls, which rolls are also provided with cams to vibrate them, (the rolls.) This evenly breaks up or distributes the ink before and while it is being applied to the plate-cylinder. This device is also well known.

100 W' is a color-reservoir. I feed one color to the cylinder D', a different color to cylinder E', to imprint upon what I will denominate the upper side of the sheet of paper. For

the lower side I feed one color to the cylinder F' and another to the cylinder G'.

I do not limit myself to any number of plate and impression cylinders, and an increase in 5 the number of these cylinders will render it possible to increase the number of colors impressed upon the sheet.

In describing the operation of my machine I shall describe it as adapted to printing upon 10 separate and detached sheets.

The arrows indicate the directions of the various wheels and cylinders upon which they are placed.

The operation is as follows: The paper is 15 passed sheet by sheet from the feed-board B, and is grasped by the gripping mechanism R R', and is carried between the first pair of cylinders, D' O, and receives its first impression of color from the plate-cylinder D'. It is 20 then carried around between the successive pairs of impressing-cylinders and plate-cylinders until it reaches a point above the receiving-board S, when the grippers open and release their grasp, which allows it to fall down 25 upon the receiving-board. The flexible bands P P' act as carriers for the paper or material being printed, in combination with the gripping mechanism. The width of the paper being 30 printed is less than the distance between the two inner edges of the two bands P P'. The bands and the gripping mechanism also act as a delivery mechanism.

The ends of plate-cylinders F' and G' are 35 really rollers for the bands, having, however, a motion not imparted by the bands, but by cog-gearing; and the sprockets described as placed upon cylinder G' may, if desired, be placed upon cylinder F', or upon any of the inside rollers, to which motion is imparted by 40 cog-wheels equal in speed to that which it is desired to impart to the bands P P'.

In my claims I shall call the carriers of the bands "rollers;" but I intend this to be a generic term to include sprocket-wheels and devices whose peripheries, revolving around centers, drive the bands by their contact therewith. These devices are mere substitutes one for another to accomplish the object attained by my rollers.

50 To facilitate the cleansing of the web T by the sponge in trough T", I keep the sponge saturated with a solution of caustic alkali, pulverized talc saturated with benzine, or other cleansing agent.

55 The device shown in Fig. 2 is, as mentioned above, a detached cross-sectional view of the attachment between the rack or arms U', which hold the inking-rollers, and the standards U". One of these arms, as well as one of the standards, is located upon each side of the machine to sustain the inking-rollers.

The attachment is made by means of a screw, X, which passes through the heel of the arm and engages by its screw-thread in a female 65 screw-thread in standard U". The part of the screw setting in the heel of the arm is not

threaded, and the hole in the heel of the arm which receives it is countersunk to receive the screw-head. By such a construction I am enabled at any time to detach the whole inking-roller mechanism from the machine by removing the screws X.

It will be noted that the front and rear standards or supports of the frame A are widely separated one from the other, and the transverse rollers and cylinders are mounted upon these parts, thus leaving a large open transverse interior space, which will enable an operator to enter into the interior of the machine and cleanse or adjust parts which would otherwise be difficult of access.

It will be evident that my machine may be used as a combined lithographic and letter press, as one of the plate-cylinders may print upon one side of the paper in type, while the next 85 cylinder or cylinders may give a lithographic impression upon the other side. It may be used as an ordinary printing-press, color-press, or as a perfecting-press, designed to print patterns in colors on one or both sides 90 of a sheet, or as an ordinary lithographic press to print in one or several colors on one or both sides of a sheet.

Any number of sets of plate and impression cylinders may be used for printing in several 95 colors without departing from the main features of my invention, whether the printing is upon one or both sides of the paper.

What I claim as new is—

1. In a printing-machine, the combination 100 of the endless flexible bands P P', gripping mechanism R R', and rollers within the space inclosed by the bands, from one of which rollers motion is imparted to the bands, the whole constituting a carrier and deliverer for the material being printed, plate-cylinder D' outside the carrier, with its compressing-cylinder O within the same, and the plate-cylinder F' within the carrier and its compressing-cylinder O' outside the carrier, substantially as described.

2. In a printing machine, the combination 105 of the endless flexible bands P P', gripping mechanism R R', and rollers within the space inclosed by the bands, from one of which rollers motion is imparted to the bands, the whole constituting a carrier and deliverer for the material being printed, and a plate-cylinder upon one side of the carrier to imprint the material being carried, with an impressing-cylinder 110 upon the other side of the carrier, directly opposite the plate-cylinder, and band or web T, roller T', trough T", and sponge T", said band or web passing around rollers T', O', and N", substantially as and for the 115 purpose described.

3. In a printing-machine, the combination 120 of the endless flexible bands P P', nipping mechanism R R', carried by the bands, and rollers within the space inclosed by the bands, from one of which rollers motion is imparted to the bands, the whole constituting a feeding

device, a carrier while the sheet is being printed on both sides before being released, and a deliverer of the material printed, plate-cylinder D' and E' on the outside of the bands, 5 and the impression-cylinders attached to gear-wheels J and K on the inside of the bands, and plate-cylinders F' and G' on the inside of the bands, and the impression-cylinders at- tached to the gear-wheels N and M on the outside of the bands, substantially as and for the purposes described.

WILLIAM H. R. TOYE.
